DOCTOR KNIVES

Eric Smith, Bury, and Thomas Scholes, Holcombe Brook, near Bury, England, assignors to D. S. T. Pattern and Engineering Company Limited, a British company of Great Britain, Northern Ireland, and the Isle of Man

Filed Dec. 4, 1962, Ser. No. 242,245

7 Claims. (Cl. 15—256.51)

This invention relates to doctor knives, such as are used in connection with the roller or cylinder of a paper-making, bleaching, dyeing or printing machine.

A basic requirement of any doctor knife is that the pressure of the blade against the coating roller or cylinder shall be as uniform as possible throughout its length, but it is believed that the doctor knife forming the subject of our prior Patent No. 2,914,788 was the first to achieve any satisfactory degree of uniformity of blade pressure when applied to rollers or cylinders of substantial length and/or subjected to high temperatures such as occur in paper-making machinery.

Under such conditions the previously known doctor knives proved unsatisfactory since their blades were adversely influenced by the inevitable sagging or distortion of their supporting means and were also unable sufficiently to accommodate themselves to the substantial non-cylindricality or "camber" which a long roller or cylinder will often exhibit.

In the patented doctor knife aforesaid the blade or blade-assembly is mounted in a channel-like holder in such manner as to locate against the base of the channel and to bear upon a resilient fulcrum extending longitudinally of the latter near its mouth, the part of the blade or blade-assembly between such fulcrum and the channel base being engaged between two opposed longitudinally-disposed abutments which hold the blade or blade-assembly clear of the channel walls and at least one of which is a tube inflatable to urge the free edge of the blade against the associated roller or cylinder with an adjustable pressure distributed uniformly along its length.

The resultant freedom of the blade to float within its holder renders it substantially unaffected by any sagging or distortion to which such holder is subject and enables very heavy "cambers" to be accommodated, while, if the three resilient members aforesaid (or at least the two abutments) consist of tubes, the optimum setting of the blade can quickly be obtained by adjustment of their respective inflation pressures.

However, the accommodation within it of two opposed inflatable tubes necessarily renders the channel-like holder of the patented doctor knife somewhat bulky in a direction perpendicular to the blade, and prolonged experience with such device in paper-making machinery has shown that, even when its free edge is "faired" by a spring plate bearing against the blade, the upper part of the holder tends to hinder the passage of the paper or pulp removed by the blade and may lead to blockages between adjacent rollers or cylinders.

The object of the present invention is to provide an alternative construction of doctor knife which is not subject to the above-mentioned drawback, while providing substantially the same uniformity of pressure along the length of the blade as the patented device, together with equivalent capacity for adjustment of the blade to an optimum position and for accommodation thereof to heavily "cambered" rollers or cylinders.

A doctor knife according to the present invention comprises a rigid carrier having a flat flange directed towards the associated roll, roller or cylinder. A shaft is positioned parallel to the axis of the roll and secured to the

2

side of said flange adjacent said roller or cylinder with capacity for localized flexure and radial movement. A plurality of rocking levers, which may be identical to each other, are fulcrummed side-by-side upon said shaft and have corresponding arms cranked away from said roller or cylinder so as to clear the free edge of said flange. A doctor blade is detachably secured to the cranked ends of the several levers through the medium of a flexible backing plate secured to said ends. Inflatable tubes are interposed between said levers and said flange at opposite sides of the said shaft.

In order that the present invention may be readily carried into effect, it will now be described with reference to the accompanying drawings, wherein:

FIG. 1 is a fragmentary front elevation of one form of doctor knife embodying the present invention;

FIG. 2 is a section taken along the line 2—2 of FIG. 1;

FIG. 3 is a detail view of a part of the embodiment of FIG. 1;

FIG. 4 is a fragmentary end elevation of the embodiment of FIG. 1;

FIG. 5 is a fragmentary section taken along the line 5—5 of FIG. 4; and

FIG. 6 is a fragmentary plan view of the embodiment of FIG. 1.

In the example illustrated, the rigid carrier portion of the doctor knife consists of a stout rolled-steel angle 10 somewhat longer than the roll, roller or cylinder 11 to be doctored and having welded to the outer side of one of its flanges two square-section bars 12 whose projecting ends are turned to form aligned trunnions 13 whereby the carrier is mounted in suitable brackets for oscillation about an axis parallel to that of the roll, roller or cylinder 11 and adjacent the periphery of the said roll.

The other flange of the rolled-steel angle 10 extends towards such periphery and has screwed into it a row of small blocks 14 with aligned clearance holes 15 for a fulcrum shaft 16 of, for example, $\frac{1}{16}$ inch diameter, which extends parallel to the axis of the trunnions 13 for the full length of the angle-section carrier 10.

Freely mounted on this shaft 16 are a series of rocking levers 17, a plurality of these such as, for example, six, being accommodated between consecutive bearing blocks 14 with a minimum of clearance between their lateral faces. Each of such levers which may be about 1 inch wide for the most part and each may have a relatively thin portion through which the fulcrum shaft 16 passes, so that the presence of the bearing blocks 14 does not interfere with the uniform spacing of the levers 17 along such shaft.

The shaft 16, positioned endwise by collars 18, is mounted non-centrally with reference to the adjacent flange of the angle-section carrier 10, so that each lever 17, which extends the full width of such flange, has a short inner arm 19 and a long outer arm 20. Inflatable tubes 21 and 22 of correspondingly different cross-sectional area are positioned between and engage the carrier flange aforesaid and coplanar flat faces of the arms 19 and 20.

The two tubes, which may be initially of circular section of, for example, 1 inch and $1\frac{1}{4}$ inches in diameter, respectively, are flattened at opposite ends to enter elongated tapered holes in plates 23 supported upon the extremities of the fulcrum shaft 16. Secured by screws 24 to the outer face of each end plate 23 are a pair of complementary tapered plugs 25 whereby the tubes are secured within the elongated holes aforesaid, two of these plugs being drilled and tapped at 26 for connection by suitable adaptors to a source of pressure fluid (e.g. air).

The long outer arm 20 of each lever 17 extends in front of the free edge of the adjacent carrier flange and is cranked to provide a flat terminal portion 27 which is

spaced from such flange and is parallel to the surfaces engaged by the inflatable tubes 21 and 22.

A flexible metal plate 28 overhanging both forwardly and rearwardly as well as at the ends of the row of levers 17, is suitably secured, such as by being riveted, at 29 to the several flat terminal portions of the levers. The levers 17 are rebated at their front ends to accommodate a hard steel blade 30 between themselves and the backing plate 28; projecting tabs 31 on such blade engaging with locating recesses 32 in the rebated parts of the levers 17.

It will be appreciated that the levers 17 form a series of supporting fingers for the blade 30, which is thus able to flex freely in a longitudinal direction while bearing against the roll, roller or cylinder 11.

The fulcrum shaft 16 is likewise free to flex, due to its small diameter and substantial clearance in the bearing blocks 14, so that no appreciable sag or distortion can be transmitted thereto from the carrier angle 10.

The varying angular positions of the several levers 17, which enable the edge of the blade 30 to contact the roller or cylinder 11 with uniform pressure throughout its length, are accommodated by the inflated tubes 21 and 22 which act in opposition to determine such pressure and the attitude of the blade with reference to the roller or cylinder periphery.

It will be appreciated that by adjusting the inflation pressures in the tubes 21 and 22 the optimum setting of the blade 30 is readily achieved.

The recommended procedure is to inflate the smaller tube 21 to 3 or 4 lbs. per sq. inch and then set the carrier 10 so that there is a gap of approximately 1 1/4 inches between the edge of the blade 30 and the surface of the roll, roller or cylinder 11. The pressure in the tube 21 is then released and the larger tube 22 is inflated, up to a maximum of 12 lbs. per sq. inch until the blade engages the surface aforesaid, the carrier 10 being adjusted towards or away from the roller or cylinder until trial by means of a suitable gauge 33 indicates that the plane of the blade 30 is inclined at 30 to 35 degrees to the tangent at the point of contact.

The clean outer surface of the blade-holder represented by the backing plate 28 offers no obstruction to the paper or pulp removed from the roll, roller or cylinder 11 by the blade 30 and the extension of the backing plate 28 above the carrier 10 ensures an easy passage for such material.

If it should be desired to doctor the lower part of the roll, roller or cylinder 11 instead of its upper part as shown, the levers 17 may be mounted in an inverted position with reference to the carrier angle 10 and the tubes 21 and 22 may be disposed above said carrier.

We claim:

1. Roll doctor apparatus adapted to be used with a roll, said apparatus comprising, in combination, a substantially rigid carrier having a flange directed towards the roll with which said apparatus is to be used; a shaft positioned substantially parallel to the axis of the roll and secured to said flange with capacity for localized flexure and radial movement; a plurality of identical rocking levers fulcrummed side-by-side upon said shaft and having corresponding arms cranked away from the roll so as to clear the free edge of said flange; a flexible plate secured to the cranked ends of said levers; a doctor blade detachably secured to said flexible plate and projecting beyond the said flexible plate towards the roll; and inflatable tubes interposed between said levers and said flange at opposite sides of said shaft.

2. Roll doctor apparatus adapted to be used with a roll, said apparatus comprising, in combination, a substantially rigid carrier having a flange directed towards the roll with which said apparatus is to be used; a row of bearing blocks affixed to said flange; a shaft having radial clearance in said blocks and supported thereby with its axis substantially parallel to that of the roll; a

plurality of rocking levers fulcrummed side-by-side upon said shaft and having corresponding arms cranked away from the roll so as to clear the free edge of said flange; a flexible plate secured to the cranked ends of said levers; a doctor blade detachably secured to said flexible plate and projecting beyond the said flexible plate towards the roll; and inflatable tubes interposed between said levers and said flange at opposite sides of said shaft.

3. Roll doctor apparatus adapted to be used with a roll, said apparatus comprising, in combination, a substantially rigid carrier having a flange directed towards the roll with which said apparatus is to be used; a row of bearing blocks affixed to said flange; a shaft having radial clearance in said blocks and supported thereby with its axis substantially parallel to that of the roll; a plurality of rocking levers fulcrummed upon said shaft and having corresponding arms cranked away from the roll so as to clear the free edge of said flange, a group of said levers being disposed between each of said bearing blocks and the next with minimal clearance between their lateral faces; a flexible plate secured to the cranked ends of said levers; a doctor blade detachably secured to said flexible plate and projecting beyond the said flexible plate towards the roll; and inflatable tubes interposed between said levers and said flange at opposite sides of said shaft.

4. Roll doctor apparatus adapted to be used with a roll, said apparatus comprising, in combination, a substantially rigid carrier having a flange directed towards the roll with which said apparatus is to be used; a shaft positioned substantially parallel to the axis of the roll and secured to said flange with capacity for localized flexure and radial movement; a plurality of rocking levers fulcrummed side-by-side upon said shaft and having corresponding arms cranked away from the roll so as to clear the free edge of said flange; a flexible plate secured to the cranked ends of said levers and projecting beyond the said levers towards the roll; a doctor blade detachably engaged between the ends of said levers and the part of said plate projecting beyond the said levers; and inflatable tubes interposed between said levers and said flange at opposite sides of said shaft.

5. Roll doctor apparatus adapted to be used with a roll, said apparatus comprising, in combination, a substantially rigid carrier having a flange directed towards the roll with which said apparatus is to be used; a shaft positioned substantially parallel to the axis of the roll and secured to said flange with capacity for localized flexure and radial movement; a plurality of rocking levers fulcrummed side-by-side upon said shaft and having corresponding arms cranked away from the roll so as to clear the free edge of said flange; a flexible plate secured to the cranked ends of said levers and projecting beyond the said levers towards the roll, the ends of said levers being rebated where overhung by said plate; a doctor blade inserted between said ends of said levers and said plate; locating tabs projecting from said doctor blade to engage recesses in said rebated ends of said levers; and inflatable tubes interposed between said levers and said flange at opposite sides of said shaft.

6. Roll doctor apparatus adapted to be used with a roll, said apparatus comprising, in combination, a substantially rigid carrier having a flange directed towards the roll with which said apparatus is to be used; a shaft positioned substantially parallel to the axis of the roll and secured to said flange with capacity for localized flexure and radial movement; a plurality of rocking levers fulcrummed side-by-side upon said shaft, that arm of each such lever which extends towards the roll being relatively long and cranked to bring its free end to the side of said flange remote from said shaft; a flexible plate secured to the cranked ends of said levers; a doctor blade detachably secured to said flexible plate and projecting beyond the said flexible plate towards the roll; and an inflatable tube interposed between the shorter arms of said levers and said flange, and a larger inflatable tube

interposed between said flange and the cranked arms of said levers.

7. Roll doctor apparatus adapted to be used with a roll, said apparatus comprising, in combination, a substantially rigid carrier having a flange directed towards the roll with which said apparatus is to be used; a shaft positioned substantially parallel to the axis of the roll and secured to said flange with capacity for localized flexure and radial movement; a plurality of rocking levers fulcrummed side-by-side upon said shaft and having corresponding arms cranked away from the roll so as to clear the free edge of said flange; a flexible plate secured to the cranked ends of said levers; a doctor blade detachably secured to said flexible plate and projecting be-

yond the said flexible plate towards the roll; inflatable tubes interposed between said levers and said flange at opposite sides of said shaft; tube plates having inwardly tapering holes to receive opposite ends of said tubes; and tapered plugs secured to said tube plates and engaged in said tube ends to secure said tube ends in said tube-plate holes, two of said plugs being drilled for introduction of pressure fluid into said tubes.
